UNITED STATES PATENT OFFICE.

FRANK D. SAYLOR, OF PITTSBURGH, PENNSYLVANIA.

CONDUIT FOR ELECTRICAL CONDUCTORS.

1,049,771.

Specification of Letters Patent.

Patented Jan. 7, 1913.

Application filed February 26, 1910. Serial No. 546,115.

To all whom it may concern:

Be it known that I, FRANK D. SAYLOR, a citizen of the United States, residing at Pittsburgh, in the county of Allegheny and 5 State of Pennsylvania, have invented certain new and useful Improvements in Conduits for Electrical Conductors, of which the following is a specification, reference being had therein to the accompanying drawing.

My invention consists in an improvement in tubular conduits for electrical conductors. The object of the invention is to provide a tube having qualities of strength, flexibility, insulation and non-combustibility and it consists in its entirety of an inner layer of fabric formed from a continuous strip upon a mandrel having its edges abutting to form a continuous smooth interior 20 and exterior; wrapping threads laid spirally around the tube as thus formed in process; a coating of tarry or other similar bituminous material; covering strips of fibrous material laid spirally around the tube 25 and embedded in said coating with intervening spaces through which the coating exudes, and a final covering of woven fabric and an outer coating therefor.

In the drawings:—Figure 1 represents the 30 operation of forming the initial inner tube upon a mandrel and the application of the wrapping threads. Fig. 2 is a cross sectional view on the line II. II. of Fig. 1. Fig. 3 is a view of the tube showing successive portions 35 of the same broken away and illustrating the successive layers and the application of the same. Fig. 4 is an enlarged cross sectional view through a finished tube on the line IV. IV. of Fig. 3.

40 In the operation of making the tube, a flat strip 2 of any suitable fabric as woven cloth, canvas or duck, is formed upon a mandrel 3 into a tube 4, the edges of which abut as indicated at 5 whereby to provide a continuously smooth exterior and interior, the strip 2 having been previously treated with 45 a solution of alum, silicate of soda, and powdered mica or other non-inflammable substance to render it fireproof. The advantage of this construction is that in the 50 finished tube the interior is completely circular, offering no obstructions or inequalities to interfere with the passage of the electrical conductors when introduced, while 55 the exterior is also truly cylindrical, insuring the cylindrical form of the resulting

completed tube, and facilitating the compact and even application of the successive layers of material. As the longitudinal strip of fabric 2 is thus formed into the cylindrical tube and while still upon the mandrel 3, it is wrapped by threads 6, 6, preferably two such threads being employed, laid around the tube-in-process spirally as indicated, whereby it is retained in cylindrical shape. 60 The application of threads 6 is accomplished by any suitable loom mechanism to insure regularity of application, the spiral winds thereof being sufficiently closely adjacent to retain the tube in shape during the successive steps of operation. The formed tube of fabric is then passed longitudinally through a bath of covering substance composed of Caladium, pitch and asphaltum, receiving the coating 7, and while such coating is still 65 in a plastic or semi-plastic condition, the tube as thus coated is annularly wound by any suitable applying mechanism with the spirally arranged strips or bands 8, 8. Said strips are of fabric or duck, or of any suitable fibrous material as preferred, cut into suitable width from sheets of the goods which have preferably been soaked or invested in a mixture of glue and cement. 70 The cement which is of mineral constituency, completely impregnates the fabric so that the resulting strips 8 are thoroughly charged or soaked with it, which with the proper proportion of glue, renders the resulting strips somewhat stiff, strong and 75 non-combustible, and having the desired qualities of insulation. 80

The fact that the coating 7 is applied by dipping the tube in a bath or passing it therethrough, clearly shows that it is fluent 85 and the material itself, to wit, Caladium pitch and asphaltum, maintains the soft plastic quality to the desired degree after application. In other words, the material does not harden, but remains in a somewhat 90 jelly-like condition of sufficient firmness to retain its shape, but still subject to pressure of any considerable degree.

As clearly shown in Fig. 3, the strips are 95 spirally wound around the tube with slight intervening spaces, through which exudes the tar as indicated at 9. By this construction the strips are firmly embedded in the coating 7 so that the initial inner tube 4, coating 7, and strips 8 are thus closely and 100 intimately associated, forming a cylindrical wall of sufficient thickness and strength, and 110

having an ample degree of flexibility. These qualities are due to the character of the materials employed and also to an extent to the manner of applying the strips 8 by 5 winding them spirally with the intervening spaces. The tube as thus formed is then covered with an outer woven fabric 10 applied by a suitable loom in the manner customary in this art, and is then covered with 10 a coating consisting of mica and glue or other adhesive material 11, and the finished tube as thus made is ready for use. Its advantages result from the complete insulation, flexibility, smooth interior, and non- 15 combustibility, and in practice it has proved to be highly efficient and well adapted to the objects in view.

Having described my invention, what I claim is:—

- 20 1. An armoring tube for conductors consisting of an inner tube of fabric formed of a longitudinal strip having a straight seam formed by abutting edges, spirally wound fine retaining threads laid around said inner tube, a coating of soft plastic material surrounding said tube and thread wrapping, an inclosing spirally wound fabricated strip covering laid tightly around said coating with intervening spiral spaces and sufficient 25 pressure to form intervening exuding ridges of said plastic material, a woven sheathing of fabric surrounding said spiral winding and exuding ridges and compactly embracing the same, and an outer adhesive finishing coating of covering material, substantially as set forth.
- 30 2. An armoring tube for conductors consisting of an inner tube of fabric formed of a longitudinal strip having a straight seam formed by abutting edges, spirally wound fine retaining threads laid around said inner tube, a coating of soft plastic material surrounding said tube and thread wrapping, a plurality of spirally wound and 35 spaced cement- and -glue- invested fabric strips laid tightly around said coating with

sufficient pressure to form intervening exuding ridges of said plastic material, a woven sheathing of fabric surrounding said spiral winding and exuding ridges and compactly embracing the same, and an outer coating of mica and glue, substantially as set forth. 50

3. An armoring tube for conductors consisting of an inner fabric tube, a coating of 55 soft plastic material surrounding said inner fabric tube, an inclosing spirally wound fabricated strip laid tightly around said coating with intervening spiral spaces whereby the plastic material fills the spiral 60 spaces and exudes therefrom, and a woven sheathing of fabric surrounding said spiral winding and exuding plastic material and compactly embracing the same, substantially as set forth. 65

4. In a flexible conduit for electrical conductors, the combination of an inner textile tube, a strip or ribbon of suitable flexible material wound spirally thereon with the edges of adjacent convolutions spaced from each 70 other, an outer textile covering, and a coating of tar surrounding the inner tube and extending through the spaces of the spiral strip into contact with the outer textile covering, substantially as set forth. 75

5. In a flexible conduit for electrical conductors, the combination of an inner textile tube, a strip or ribbon of suitable flexible material wound spirally thereon with the edges of adjacent convolutions spaced from 80 each other, an outer textile covering, and a coating of tarry material surrounding the inner tube and extending through the spaces of the spiral strip into contact with the outer textile covering, substantially as set forth. 85

In testimony whereof I affix my signature in presence of two witnesses.

FRANK D. SAYLOR.
